CLAIM

The ornamental design for an 30 amp electrical connector head replacement receptacle, as shown and described.

DESCRIPTION

FIG. 1 is a bottom, right side, rear perspective view of an embodiment of an 30 amp electrical connector head replacement receptacle embodying our design;

FIG. 2 is a rear elevational view thereof;

FIG. 3 is a front elevational view thereof;

FIG. 4 is a top, left side, front perspective view thereof;

FIG. 5 is a left side elevational view thereof and the right side elevational view being a mirror image;

FIG. 6 is a top plan view thereof; and,

FIG. 7 is a bottom plan view thereof.

The broken lines showing portions of the 30 amp electrical connector head replacement receptacle are included for the purpose of illustrating environmental structure and form no part of the claimed design.
